FILING CABINET

Carl W. Sundberg, Bloomfield Hills, and Montgomery
Ferar, Huntington Woods, Mich., assignors to Sperry
Rand Corporation, New York, N.Y., a corporation of Delaware

Filed Apr. 16, 1962, Ser. No. 69,739

Term of patent 14 years

(Cl. D33—19)

FIG. 1.

FIG. 2.

FIG. 3.

FIG. 1 is a perspective view of a filing cabinet embodying our new design;

FIG. 2 is a front view thereof;

FIG. 3 is a side elevation as seen from the right of FIG. 2, the side opposite thereto being similar in appearance and the back of the cabinet being plain.

The dominant feature of our design for the filing cabinet disclosed is characterized by the drawer pulls and label holders each having the contour and configuration shown.

We claim:

The ornamental design for a filing cabinet, substantially as shown and described.
